SINGLE CHANNEL ADAPTER FOR MULTIPLEX SYNCHRONOUS PRINTERS

James A. Spencer, Teaneck, N. J., assignor to
Radio Corporation of America, a corporation of
Delaware

Application February 10, 1940, Serial No. 318,234

12 Claims. (Cl. 178—4)

This invention relates to mechanism for use in radio and wire telegraph systems. In multiplex telegraphy, using equal-length code characters, a plurality of channels, each having its own tape transmitter at the sending station and printing mechanism at the receiving station, are successively assigned to a radio or wire link for the duration of one code character. This enables one to utilize all the time allotted to each channel for the sending of the messages, because the local printing operations for one channel, such as setting up the tape combinations and operating the printer, are taken care of while another channel is sending on its allotted time.

In simplex telegraphy for equal-length code characters, the whole circuit time cannot be utilized for transmission of the characters of the code signals except by providing a storage means for the signals. In my co-pending application, Serial No. 252,179 filed January 21, 1939, I have disclosed sending and receiving mechanism for single channel systems that permits one to utilize all the circuit time for the transmission of the message by providing electromagnetic storing relays operating in connection with synchronous distributors. This invention is an improvement on the invention of this application, in which mechanical apparatus takes the place of the storing relays.

An object of this invention is to provide mechanical locking mechanism for storing signals to be fed to a synchronous printer.

Another object of this invention is to provide an adapter that stores the signal operations by cam and lever mechanism, with elimination of electromagnetic storing relays.

Another object of the invention is to provide mechanical devices for closing the contacts of the printer electromagnets by a shaft rotating at a speed proportional to the keying speed at the distant transmitter, with mechanical means for storing the signals while the printing functions are being performed.

Other objects will appear in the following description, reference being had to the drawings in which:

Fig. 1 is an elevation of the adapter mechanism.

Fig. 2 is a section taken along the line 2—2 of the adapter shown in Fig. 1.

Fig. 3 is a view of a transfer lever with the parts in switch closing position.

Fig. 4 is a bottom view of the switches.

Fig. 5 is a diagram showing the time of operation of the adapter mechanism.

Fig. 6 is a detail view of a selector lever and its operating cam.

Fig. 7 is a diagrammatic illustration of the synchronous printer.

Fig. 8 is a view of the battery connections for energization of the printer and associated mechanism.

Fig. 9 is a conventional diagram of part of the printer.

Fig. 10 is an end view of a modification, certain parts not being shown.

Fig. 11 is a side view of the transfer levers and switches of the modification shown in Fig. 10.

The transmitting mechanism is not illustrated in this embodiment, as it is not claimed per se herein. The transmitter is fully shown and described in my hereinbefore mentioned application and it will be sufficient merely to say that the transmitter sends out positive and negative pulses in proper time relation to form the desired code characters. The specific code employed is a seven unit equal-length code analogous to the five unit Baudot code, though the invention could be used with other codes if desired, and of course interruptions of current may be used instead of positive and negative current pulses.

The pulses formed at the transmitter are sent out over the radio or wire link, as the case may be, and are received at the receiving station. If the signals are sent out over a radio link, they are received, amplified, detected and further amplified and transmitted to the printing mechanism to line L (Fig. 1) connected to the line or signal magnet 1, the other end of the magnet coil being connected to ground G. If sent out over a wire link the transmission line is connected to line L, as well known.

The adapter mechanism shown in Fig. 1 has a shaft 2 rotated at a speed in synchronism with or proportional to that of the distributor at the transmitter. The means for producing the synchronization or proportional speed of the shaft 2 may be any of the well-known means found in the art; for example, it may be that disclosed in Mathes Patent 2,038,375, April 21, 1936.

The shaft 2 has seven cams, I, II, III, IV, V, VI, VII, each cam having a circular or cylindrical surface, except for a small fraction thereof constituted by a cam projection 4 (Fig. 6). These cams are spaced apart by washers such as 5 and the cam projections are spaced equidistant around the shaft so that an end view of the cam assembly as seen in Fig. 2 in dotted lines has somewhat the appearance of a seven-pointed

star. Each of the seven cams has a cam follower on selector lever 6 pivoted at 7. The cam follower of the selector lever is held against its cam by a spring 8. Each of the seven selector levers, all being identical, has a swivel connection at the end 9 with a sword 10 having two projections 11, 12 which are adapted to engage the prongs 13, 14 of rocker arm 15 of an armature pivoted at 16 and positioned to be attracted by signal magnet 1 when it is energized. By referring to Fig. 1 it will be seen that the rocker arm 15 extends to one side so that the prongs 13, 14 surround all seven selector levers and other parts to be referred to later.

Each sword 10 is adapted, when lowered by the cam action, to engage either arm 16 or arm 17 of the T-latch 18, depending upon its position. The latch 18 engages switch lever 19 pivoted at 20 and having switch contacts 21I, 21II, 21III, 21IV, 21V, 21VI, or 21VII, one contact of which 20 is connected to a source of supply as at 22 and the other of which is connected to a wire 23I, 23II, 23III, 23IV, 23V, 23VI, or 23VII, as the case may be, that extends to selector magnets shown in Fig. 7. There are seven swords, seven 25 switch levers and seven selector magnets, so that each cam 4 controls the energization of a selector magnet.

On shaft 2 of the adapter is located a transfer cam 24 at the right of the code cams I-VII as shown in Fig. 1 and a second transfer cam 25 shown at the left of the code cams in this figure. These with their associated parts are the storing means for the signals. The two transfer cams are of the same shape, cam 25 being shown in 30 Fig. 3. The transfer cams are spaced from the other cams by washers such as 5 and are adjusted in position for timed operation as indicated in Fig. 5. The transfer cams 24, 25 have cam followers consisting of transfer bell-crank levers 26, 27 of the same general shape as the selector levers 6. Springs 28 hold the transfer levers against the cam. The ends of the transfer levers 26, 27 have pivot connections with transfer links 29 and 30 respectively. These transfer links have a suitable sliding connection with a guide and stop rod 31. Transfer link 29 has a projection 32 extending under switch levers 19 associated with cams V, VI and VII, and transfer link 30 has a projection 33 extending under the switch levers 19 for cams I, II, III and IV (Figs. 1 and 4).

When the cam follower on either of the transfer levers engages the circular part of the cam, the associated transfer link is held up so that the cross arm 32 or 33 holds the contacts 21I, etc., of the associated switch levers open so they cannot close even though a latch 18 may be in the unlatched position. Thus, to operate any one of the seven switch levers 19 it is necessary that the latch 18 be moved to the right in Fig. 2 and that the transfer link be in the down position as in Fig. 3. The transfer levers also return any closed switches to open position when their associated cam followers ride out of the cam notches.

To prevent the magnet armature or rocker arm 15 from chattering or moving from its proper position, a locking lever or latch 34 is provided. This latch engages notches in the rocker arm at 35 to hold it either in the attracted or unattracted 70 position. The latch 34 is pivoted on the rod 7 and has a cam follower 36 engaging the locking cam 37 by action of spring 38. The locking cam 37 is shown in Fig. 1, but its relation to the locking lever and the rocker arm 15 is best illus-

trated in the modification of Fig. 10. The construction is such that the rocker arm 15 cannot be moved by the magnetic pull of signal magnet 1 or by the spring 38' except when the cam follower 36 is on the high points of the cam 37, there being seven of these cam points equally spaced around the circumference as indicated in the timing diagram of Fig. 5. The rocker arm 15 can be moved by the magnet 1 or the spring 38' only when the cam follower 36 is in one of the depressions of locking cam 37. The locking cam is so adjusted in position on the shaft 2 that the magnet rocker arm 15 is locked against movement while the selection levers I-VII are riding over their respective cam projections, so that the rocker arm is held rigid while a projection on the sword 10 engages a prong 13 or 14, as the case may be, due to the elevation of the sword by movement of the selector lever over one of the cam projections, as will be referred to more in detail in describing the operation of the adapter.

In the modification of Fig. 10 the mechanism is in general the same as already described, except that the projections 39 or 40 of the transfer levers have arms 41, 42 directly engaging projections 43, 44 on the switch arms 19, projection 44 being associated with the parts connected to cams I, II, III and IV, and projection 43 with those associated with cams V, VI and VII.

The operation of the adapter will now be described in connection with the synchronous printer diagrammatically illustrated in Figs. 7 and 8, which need no detail description.

As shown in my above-mentioned application, positive and negative pulses are sent out to constitute the code character in cable code, and these at the radio receiver are converted into current and no-current indications, but of course the original signal could have been transmitted in current and no-current indications at the transmitter in accordance with the American code practice if desired.

Assuming the use of the seven unit code of my above-mentioned application and that the letter 45 A is being transmitted, there will be a pulse for the first, third and fourth code characters and no pulses for the second, fifth, sixth and seventh code characters. Since the adapter shaft 2 is being rotated in synchronism with the distributor at the transmitter or at a speed proportional thereto, the signal magnet 1 will be energized by the first pulse when cam I lifts its associated cam lever 6 by means of the cam projection 4 (Figs. 2 and 6). The armature extension or rocker arm 15 will then be in the position shown in Fig. 2. As the sword 10 is raised, projection 12 will engage prong 14 on the rocker arm. This will swing the sword over into position above arm 17 of T-latch 18. As soon as cam projection passes the cam follower, the spring 8 causes the selector lever to move the sword 10 against arm 17. Latch 18 will be moved away from the switch lever 19 associated therewith. This particular switch lever 19 will not move its contact arm into engagement with its contact 21I (Fig. 4) because transfer link 30 is in the elevated position shown in Fig. 2, since the transfer lever is at this time riding on the circular periphery of cam 25, as will be clear from an inspection of the timing diagram of Fig. 5. The switch lever, however, is unlatched and the character is thus stored for later use.

When cam II engages its cam follower in the time allotted to the second unit, no pulse is received for the letter A. Signal magnet 1 is not

energized and extension 15 is in its left hand position (not shown in the drawings). As the cam follower rides up cam II the sword is raised by the selector lever and arm 11 engages projection 13 on the extension 15. The sword point is thus moved to the right above arm 16 in latch 18. This position of the sword point for no-current characters is the one shown in Fig. 2. In this figure the signal magnet is energized but the selector is not shown in its raised position, which would have swung the sword point over into the other position. It will be clear that as the sword lowers when the selector lever cam follower rides down the projection of cam II, the latch 18 will not be moved to release the switch lever.

When the position for the third unit is reached, signal magnet 1 will be energized and cam III will operate its selector lever, sword and latch. Upon reaching the fourth position of the seven-character code, cam IV will operate its T-latch and release its switch lever. However, at this time the contacts 21I, 21III and 21IV will not close because they are held open by the projection 33 on the transfer link 30. Since the letter A has no current pulses for the fifth, sixth and seventh positions, latches 18 are not unlatched by their cams V, VI and VII. However, about the time the fifth position is reached (see diagram of Fig. 5), transfer lever 26' rides down into its cam notch 45' to the position shown in Fig. 3 (note also Fig. 5) and the lowering of projection 33 on link 30 permits switch contacts 21I, 21III and 21IV to close.

The closing of contacts 21I, 21III and 21IV puts potential on lines 23I, 23III and 23IV and energizes the first, third and fourth selector magnets (counting from the right in Fig. 6). The first magnet attracts its armature 46 and catch 47 snaps over the end of the armature and holds it in the notch 48 of the selector bar 49. The armature and latch for only one selector magnet are shown, but all of the selector magnets have similar armatures and latches. The energization of magnets 23II and 23III likewise projected their armature ends into notches in their selector bars where they are held by their latches.

Switches 21V, 21VI and 21VII do not close when their cams V, VI and VII operate the selector levers (Figs. 2 and 4) because no current pulses are received to energize magnet 1. Nothing further happens at the printer of Fig. 7 for the time allotted to the fifth, sixth and seventh characters, but it should be noted that switch levers 19 for the cams I, II (III also, if it has been previously operated) and IV were placed in position for the unit of the next succeeding letter shortly after the position was reached for the sixth signal character (see diagram of Fig. 5). Therefore, before the first described revolution of shaft 2 is completed, additional signal units can be received and stored in the first four positions of the succeeding revolution of the shaft since the selector switch levers 19 were returned to their initial position when the transfer levers were raised by their cams leaving the cam notches.

When the second position of the succeeding revolution is reached, contact 50 connects brushes 51 and 52 (Figs. 1 and 5) and places potential on line 53 (Figs. 1 and 7). This energizes relay 54 through contacts 55 previously closed by the energization of selector magnets 23I, 23III and 23IV. The energization of relay 54 closes switch 56 and energizes operating magnet 57.

The armature 58 is attracted and plunger 59 moves carriage 60 to the left in Fig. 7.

Since the seven selector magnets and their respective armatures are mounted on carriage 60, the selector bars 49, 61 and 62 are moved with the carriage because the projecting ends of the armatures of those selector magnets engage the edges of notches in the selector bars. The remaining selector bars are not moved with the carriage. Shortly before the motion to the left is completed, trip 63 engages latch 47 and permits the armatures (one only being shown) to spring back into place. The armatures are freed from friction against the ends of notches 48 etc. at this time by leaf spring 64 entering notches 65 in the three selector bars, which snaps the selector bars slightly to the left. Selector magnets 23I, 23III and 23IV then resume their normal condition. When the three selector bars reach their extreme left-hand position notches 66 in the three selector bars corresponding to the letter A are in alignment. Pull bar 67 shown more in detail in Fig. 9 is then in position to drop into these aligned notches, but it is held from this movement by the printing bail 68 engaging hump 69 on the pull bar.

When the carriage reaches its extreme movement to the left it opens switch contacts 70 and breaks the continuity of the holding circuit of relay 54. This de-energizes the relay and opens the contacts 56, which in turn de-energizes carriage operating magnet 57. The carriage return spring 71 thereupon returns the carriage to the right against stop 72.

As the selector bars 49, 61 and 62 moved to the left in the initial motion of the carriage they engaged return lever 73 and turned it around its center point against the tension of its spring 74. Latch 75 immediately snapped into position and held the return lever so that the selector bars were not returned to the right at that time.

As the return lever 73 snapped into the notch of latch 75, printing contacts 76 closed and printing relay 77 was energized. This closed contacts 78 and energized printing solenoid 79. This solenoid pulls the armature 80 downwards with its extension 81 which is pivoted to printing bail 68, the bail being pivoted at an intermediate point 82. This moves the bail upwards (Fig. 9) and permits the pull bar 67 for the letter A to drop into the aligned notches 66 etc. in the operated selector bars. As it does this, the upwardly moving projection 82' engages the hump 69 in the pull bar and moves it upwards with the bail. This throws the type bar 83 downwards and strikes the type-pallet against the ribbon on platen 84. This prints the letter A.

Just at the time that the armature 80 of the printing solenoid completed its movement, projection 84 engaged the latch 75 and permitted the return 73 to return the three operated selector bars to the right, whereupon leaf spring 64 snapped into groove 85 which holds these three bars together with the others in their initial position. At about this time projection 86 opens switch contacts 87 and deenergizes the printing relay and the printing solenoid magnet. The plunger is then returned to its initial position by spring 88 (Fig 9). This returns the pull bar and brings the printing bail 68 against the hump 69 of the pull bar and moves it outwards clear of the selector bars.

The selected letter A has thus been printed and all mechanism of the printer has returned to the original position at about the time cam

II operated its selector lever. However, as already stated, the selection of the next transmitted letter was not held up pending the operating of the printing mechanism, since the switches 19I and 19IV were in their normal position before the previous revolution was completed.

From the foregoing it will be clear how the signals corresponding to the first four units of the seven-unit code are received and printed as the letter A. When the fifth, sixth and seventh code units are used in a signal their cams, swords and T-latches will operate in a similar way at the proper time shown in Fig. 5. The switches 21V, 21VI and 21VII, however, will not close until the transfer lever 29 engages the cam depression 89 (Fig. 5) in cam 24. This takes place just before cam II operates its selector lever in the revolution succeeding the one described for the signals of letter A. The transfer lever 29 moves out upon the circular part of its cam shortly thereafter and switches 23V, 23VI and 23VII (if operated) are moved back into engagement with their T-latches 18. Hence the parts are in normal position for receiving the fifth, sixth and seventh code units at about the time the position for the third unit is reached in the adapter.

In the way described, the signals are stored and the printer operated without taking circuit time away from the parts responding to the code character pulses or indications. The system disclosed is therefore well adapted to single channel systems, though of course it can be used in multiple channel systems equally as well.

In the modification shown in Fig. 10 the operation will be the same as already described. The only difference is that the switches 19 are held in storage position by the end of the transfer levers instead of by links pivoted thereto.

Having described my invention, what I claim is:

1. In an electrical printing telegraph system for multi-unit equal length code characters, a printer having a selector magnet for each code unit, a rotatable adapter shaft, a switch in the circuit of the coil of each magnet, a latch normally holding each switch open, means operated by said shaft for releasing the latches successively at uniform time intervals in a continuous cycle, supports normally holding said switches open, and additional means operated by said shaft for releasing said supports.

2. In an electrical printing telegraph system for multi-unit equal length code characters, a printer having a selector magnet for each code unit, a rotatable adapter shaft having cams uniformly spaced therearound, there being one cam for each code unit, a switch in the circuit of the coil of each magnet, a latch normally holding each switch open, means operated by said cams for releasing the latches, supports normally holding said switches open, and additional cams on said shaft having means for releasing said supports.

3. In an electrical printing telegraph system for multi-unit equal length code characters, a printer having a selector magnet for each code unit, a signal magnet for receiving the incoming signals, a rotatable adapter shaft having cams uniformly spaced therearound, there being one cam for each code unit, a switch in the circuit of the coil of each selector magnet, a latch normally holding each switch open, plungers operated by said cams for moving the latches

to closing and opening positions, means operated by the signal magnet for directing said plungers to one of said positions on receipt of a signal and to the other position on absence of a signal, supports normally holding said switches open, and means for releasing said supports.

4. In an electrical printing telegraph system for multi-unit equal length code characters, a printer having a selector magnet for each code unit, a switch in the circuit of the coil of each magnet, a latch normally holding each switch open, means for releasing the latches at uniform time intervals in continuous cycles, a support normally holding part of said switches open, an additional support normally holding the remaining switches open, and means for releasing said supports in timed succession.

5. In an electrical printing telegraph system for multi-unit equal length code characters, a printer having a selector magnet for each code unit, a rotatable adapter shaft having cams uniformly spaced therearound, there being one cam for each code unit, a switch in the circuit of the coil of each magnet, a latch normally holding each switch open, means operated by said cams for releasing the latches, a support normally holding part of said switches open, an additional support normally holding the remaining switches open and additional cams on said shaft having means for releasing said supports in timed succession.

6. In an electrical printing telegraph system for multi-unit equal length code characters, a printer having a selector magnet for each code unit, a rotatable adapter shaft having cams uniformly spaced therearound, there being one cam for each code unit, a switch in the circuit of the coil of each magnet, a latch normally holding each switch open, plungers operated by said cams for moving the latches to closing and opening positions, means operated by the signal magnet for directing said plungers to one of said positions on receipt of a signal and to the other position on absence of a signal, supports normally holding part of said switches open, an additional support normally holding the remaining switches open, and additional cams on said shaft having means for releasing said supports in timed succession.

7. In an electrical printing telegraph system for multi-unit equal length code characters, a printer having a selector magnet for each code unit, a signal magnet for receiving the incoming signal, a rotatable adapter shaft having cams uniformly spaced therearound, there being one cam for each code unit, a switch in the circuit of the coil of each magnet, a latch normally holding each switch open, plungers operated by said cams for moving the latches to closing and opening positions, means operated by the signal magnet for directing said plungers to one of said positions on receipt of a signal and to the other position on absence of a signal, a support normally holding part of said switches open, an additional support normally holding the remaining switches open and additional cams on said shaft having means for releasing said supports in timed succession.

8. In an electrical printing telegraph system for multi-unit equal length code characters, a printer having a selector magnet for each code unit, a rotatable adapter shaft having cams, a switch in the circuit of the coil of each magnet, a latch normally holding each switch open, there being a cam, a switch and a latch associated to

gether for each code unit, means operated by each cam for releasing its latch at a predetermined point in each revolution of the shaft, a support normally holding open the switches associated with the latches released in the fore part of each revolution, an additional support normally holding open the switches associated with the remaining latches, a cam on said shaft for releasing the first-mentioned support after the last latch associated therewith has been released in that revolution, and a cam on said shaft for releasing the second-mentioned support after the last latch associated therewith has been released and before the first latch associated therewith has been released in the next revolution of the shaft.

9. In an electrical printing telegraph system for multi-unit equal length code characters, a printer having a selector magnet for each code unit, a rotatable adapter shaft having cams, a switch in the circuit of the coil of each magnet, a latch normally holding each switch open, there being a cam, a switch and a latch associated together for each code unit, a plunger operated by each cam for moving its latch to closing and opening positions at a predetermined point in each revolution of the shaft, means operated by the signal magnet for directing said plungers to one position on receipt of a signal and to the other position on absence of a signal, a support normally holding open the switches associated with the latches released in the fore part of each revolution, an additional support normally holding open the switches associated with the remaining latches, a cam on said shaft for releasing the first-mentioned support after the last latch associated therewith has been released in that revolution, and a cam on said shaft for releasing the second-mentioned support after the last latch associated therewith has been released and before the first latch associated therewith has been released in the next revolution of the shaft.

10. In an electrical printing telegraph system for multi-unit equal length code characters, a printer having a selector magnet for each code unit, a signal magnet for receiving the incoming signal, a rotatable adapter shaft having cams, a switch in the circuit of the coil of each magnet, a latch normally holding each switch open, there being a cam, a switch and a latch associated together for each code unit, a plunger operated by each cam for moving its latch to closing and opening positions at a predetermined point in each revolution of the shaft, means operated by said signal magnet for directing said plungers to one of said positions on receipt of a signal and to another position on absence of a signal, a support normally holding open the switches asso-

ciated with the latches released in the fore part of each revolution, an additional support normally holding open the switches associated with the remaining latches, a cam on said shaft for releasing the first-mentioned support after the last latch associated therewith has been released in that revolution, and a cam on said shaft for releasing the second-mentioned support after the last latch associated therewith has been released and before the first latch associated therewith has been released in the next revolution of the shaft.

11. In an electrical printing telegraph system for multi-unit equal length code characters, a printer having a selector magnet for each code unit, a signal magnet for receiving the incoming signal, a rotatable adapter shaft having cams, a switch in the circuit of the coil of each magnet, a latch normally holding each switch open, there being a cam, a switch and a latch associated together for each code unit, means operated by each cam for moving its latch to closing and opening positions at a predetermined point in each revolution of the shaft, means operated for the signal magnet for directing said plungers to one of said positions on receipt of a signal and to the other position on absence of a signal, a support normally holding open the switches associated with the latches released in the fore part of each revolution, an additional support normally holding open the switches associated with the remaining latches, a cam on said shaft for releasing the first-mentioned support after the last latch associated therewith has been released in that revolution, and a cam on said shaft for releasing the second-mentioned support after the last latch associated therewith has been released and before the first latch associated therewith has been released in the next revolution of the shaft.

12. In an electrical printing telegraph system for multi-unit equal-length code characters, a printer having a selector magnet for each code unit, a signal magnet energized and de-energized by the signals, a switch having one position for opening and another for closing the circuit of the coil of each selector magnet, separate means controlled by said signal magnet for holding each switch in one of said positions, means for cyclicly moving said separate means away from said position, each at a predetermined time in each cycle, upon the de-energization of the signal magnet at such time, additional means for holding the switches in said position and means for moving said additional means away from switch-holding position independently of the energization of said signal magnet.

JAMES A. SPENCER.
